OSCAR SIMMEN, OF ERLACH, SWITZERLAND, ASSIGNOR TO SULZER FRERES SOCIETE ANONYME, OF WINTERTHUR, SWITZERLAND

COOLING DEVICE FOR INTERNAL COMBUSTION ENGINES

Application filed August 18, 1931, Serial No. 557,802, and in Switzerland August 28, 1930.

This invention relates to internal combustion engines of the liquid fuel injection type in which the main quantity of the cooling medium for the cylinders and cylinder heads 5 passes through a closed circuit and only a part of this medium is discharged through branch pipes provided with open outlets.

According to the present invention the cooling medium flowing through the branch 10 pipes is employed to cool fuel injection devices prior to its being discharged through the open end of its associated branch pipe.

One construction according to this invention is illustrated somewhat diagrammatically 15 by way of example in the accompanying drawings, in which

Figure 1 is a section through the cylinder and frame of an internal combustion engine, and

20 Figure 2 is a plan of the arrangement illustrated in Figure 1 as applied to a six-cylinder internal combustion engine.

In the construction illustrated the engine 25 comprises a frame 1, resting upon a base plate or bed 2 and carrying a cylinder 3 provided with a cylinder head 4 in which is arranged a fuel injection valve 5 having a chamber therein through which cooling medium can be circulated. Carried by bearings in the bed 2 is a crank-shaft 6 which is connected to a piston 7 by a connecting rod 10 having a crosshead 9 and a piston rod 8.

The cooling medium is conveyed to the 30 cooling jacket 12 of each cylinder from the pipe 11 and flows thence through a pipe 13 into the cooling chamber 14 of the cylinder head 4. Part of the cooling medium escapes from the cooling chamber 14 of the cylinder head 4 by way of a pipe 15 into a common collecting pipe 16 while another part of this 35 cooling medium is conveyed through a pipe 19 into the cooling chamber of the fuel injection device 5 whence it flows by way of a pipe 17.

40 Each of the several pipes 17 from the cooling chamber of the various fuel injection devices is provided with an open outlet 20 discharging into a collecting trough 18 so that the flow of cooling medium from the cooling 45 chamber of each fuel injection device 5

through its pipe 17 can be observed, means being provided for permitting the escape of the cooling medium from the trough 18. The part of the cooling medium flowing through the branch pipes 19 and 17 is thus used both for cooling the fuel valve and for enabling the working of the cooling arrangement to be checked, and owing to the fact that the cooling medium delivered to the cooling chamber of each fuel valve passes first through the cylinder and cylinder head, any choking within the cooling chambers of the valves is avoided since the impurities tend to settle in the more accessible cooling chambers of the cylinder and cylinder head. 55

50 It is to be understood that if desired the cooling medium delivered to the cooling chambers of the valves may be derived directly from the cooling chambers of the cylinders or of the crosshead guides where cooled crosshead guides are employed. 60

65 I claim:

In an internal combustion engine, in combination a plurality of cylinders, a piston reciprocating in each of said cylinders, a cooling jacket surrounding each of said cylinders, a pipe connected to the lower end of each of said cooling jackets for conveying cooling liquid to said jackets, a cylinder head carried by each of said cylinders surrounded by a cooling space, a passage connecting each of said cooling spaces with said jacket of the corresponding cylinder, a fuel injection valve arranged in each of said cylinder heads, a chamber in each of said valves, a pipe connecting the cooling space of each cylinder head to said chamber in the corresponding valve, a pipe having an open outlet leading from each of said chambers and a trough common to all said open ended pipes. 70

75 In testimony whereof I have affixed my signature.

OSCAR SIMMEN.
